UNITED STATES PATENT OFFICE.

JOSEPH CHVOJKA, OF PHILADELPHIA, PENNSYLVANIA.

AERIAL ADVERTISER.

Application filed January 24, 1925. Serial No. 4,417.

My invention relates to new and useful improvements in an aerial advertiser, and has for its primary object to provide in a device of this character, a sign having means 5 to revolve the same.

A further object of the invention is to provide an aerial advertiser including a balloon, a cable or other equivalent means for holding the balloon captive and a sign rev- 10 olubly mounted on the cable.

A further object of the invention is to provide an advertising device consisting of a balloon, a cable connected therewith and revolving a sign, means to revolubly mount 15 the sign on the cable and electrically actuated means also supported by the cable to revolve the sign.

A still further object of the invention is to provide means supported by the cable for 20 illuminating the sign.

With these ends in view, this invention consists in the details of construction and combination of elements hereinafter set forth and then specifically designated by 25 the claims.

In order that those skilled in the art to which this invention appertains, may understand how to make and use the same, I will describe its construction in detail, 30 referring by numerals to the accompanying drawings forming a part of this application, in which:—

Fig. 1, is a side elevation of the aerial advertiser constructed in accordance with 35 my invention.

Fig. 2, is an enlarged sectional elevation of the sign elements.

Fig. 3, is a bottom plan view of Fig. 2 with the light shield removed and a portion 40 of the sign broken away.

In carrying out my invention as here embodied, 2 represents a balloon of usual well known construction and of any suitable size and shape suited for the purpose. About 45 this balloon is a harness which includes a desirable number of straps and for convenience of illustration this harness is shown as including a horizontal strap 3 passing around the longitudinal center of the balloon and a plurality of straps 4 passing around the smaller circumferences at different points.

To this harness and more particularly the central strap 4 is attached one end of a cable 55 the other end of which may be wound upon a drum 6 fixed to a shaft 7 journalled in

suitable bearings 8 of a support 9 and on this shaft may be fixed a pulley 10 over which runs a belt also passing around the pulley 12 on the shaft of the electric motor 60 13 or equivalent prime mover whereby the balloon may be "let out" or "withdrawn" as the case may be. In order to further strengthen the connection between the cable and balloon a plurality of guides 14 are 65 provided which are fastened to the harness at suitable points and to the cable 5 some distance below the balloon.

On the cable 5 at a suitable distance below the balloon is fixed a bearing 15 to receive 70 one end of the tube 16 which freely rotates on said bearing and the other end of said tube is connected with one ring 17 of a ball bearing while the other ring 18 thereof is suitably mounted on the tubular support 19 75 having connection with a socket 20 on the electric motor 21. The motor 21 is supported by the cable 5 and as here shown portions of said cable pass around both sides of the motor and then enter the tubular support 80 19 to suitable openings where the cable again continues as a whole through the tubular support 19, the tube 16 and the bearings 15.

The tube 16 acts as a hub for the sign 85 22 which latter includes a skeleton like frame including radiating arms 23 having their inner ends suitably fixed to the upper end of the tube or hub 16 and their outer ends secured to upright ribs 24 while adjacent 90 the lower ends of said ribs are secured the outer ends of the angular arms 25, the inner ends of which are fixed to the tube or hub 16 adjacent its lower end.

The lower arms are bent upward intermediate their ends in order to provide for their passage about the illuminating devices to be presently described. The ribs 24 converge toward their lower ends so that the sides of the skeleton frame are inclined and 100 said sides of this frame are covered with a suitable material 26 preferably transparent or translucent and I have found that a celluloid material is desirable as it has considerable strength, is light and sufficiently transparent to permit the penetration of light rays as well as making a good base for painting or otherwise delineating advertisements thereon.

As the tube or pipe 16 is journalled to 110 revolve and since the sign is fixed thereto the latter will revolve with the pipe and in order

to revolve said sign a desired number of revolutions per minute I fix a gear 27 to the tube 16 which meshes with a gear 28 on a shaft 29 carried by the stationary tubular support 19 while in fixed relation to the gear 28 is a pulley 30 over which passes a belt 31 also passing over a pulley 32 on the shaft of the motor 21.

In order to illuminate the sign a plurality of brackets 33 are suitably fixed to the stationary tubular support 19 and projecting into the sign where illuminating devices 34, such as electric lamps are suitably mounted upon said brackets. The wires for supplying current to the electric lamps 34 and the motor 21 supply the necessary electric current from a suitable source of electric energy such as the surface lines of a building and these wires may, if found desirable, be wrapped about the cable or other parts leading to the points of use.

As it is contemplated to position the advertisements on this device in an elevated position it is desirable to shut off the lights from the view of observers I provide a shield 35, which as here shown, may consist of a flat piece of material fixed to the lamp brackets and of sufficient size to extend across the lower end of the sign.

From the foregoing description it will be readily noted that when the motor 13 is operated in the proper direction the cable 5 will unwind from the drum 6 and the balloon 2 will ascend to the desired height. After setting the balloon the current may be turned on to the motor 21 so that the sign will be revolved in order that the advertising matter will be visible to persons below in all directions and during dark days or at night the current may be turned on to the lamps 34 so that the sign will be visible during darkness as well as in the daytime.

By providing the revolving sign with wings 36 the power of the wind may be utilized for revolving said sign when the motor 21 is out of order or said motor may be entirely eliminated.

Of course I do not wish to be limited to the exact details of construction as herein

shown as these may be varied within the 50 limits of the appended claims without departing from the spirit of my invention.

Having thus fully described my invention, what I claim as new and useful is:—

1. An aerial advertising device including 55 a balloon, a cable, means for connecting said cable to the balloon, means for reeling said cable in and out, an electric motor supported by the cable, a tubular support connected with the motor and through which the cable 60 passes, said tubular support being in fixed relation to the cable, a tube on the cable above the tubular support, a ball bearing between the tube and said tubular support, a bearing fixed on the cable and projecting 65 into the upper end of the tube, driving means for transmitting motion from the motor to said tube, a skeleton sign frame connected with said tube to revolve therewith, transparent material covering the sides of said sign 70 frame on which advertisements may be delineated.

2. An aerial advertising device including 75 a balloon, a cable, means for connecting said cable to the balloon, means for reeling said cable in and out, an electric motor supported by the cable, a tubular support connected with the motor and through which the cable passes, said tubular support being in 80 fixed relation to the cable, a tube on the cable above the tubular support, a ball bearing between the tube and said tubular support, a bearing fixed on the cable and projecting into the upper end of the tube, driving 85 means for transmitting motion from the motor to said tube, a skeleton sign frame connected with said tube to revolve therewith, transparent material covering the sides of said sign frame on which advertisements may be delineated, brackets fixed to the tubular support with their upper ends projecting 90 across the lower end of the sign frame and supported by the brackets. 95

In testimony whereof, I have hereunto affixed my signature.

JOSEPH CHVOJKA.
